UNITED STATES PATENT OFFICE.

JAMES T. HALL, OF COALINGA, CALIFORNIA, ASSIGNOR TO BUNTING IRON WORKS, OF COALINGA, CALIFORNIA, A CORPORATION OF CALIFORNIA.

CROWN-BLOCK FOR OIL-DERRICKS.

1,117,668.

Specification of Letters Patent. Patented Nov. 17, 1914.

Original application filed November 15, 1910, Serial No. 592,422. Divided and this application filed December 14, 1911. Serial No. 665,687.

To all whom it may concern:

Be it known that I, JAMES T. HALL, a citizen of the United States, residing at Coalinga, in the county of Fresno and State of California, have invented certain new and useful Improvements in Crown-Blocks for Oil-Derricks, of which the following is a specification.

The invention relates to an improved crown block for supporting or sustaining the operative sheaves for derricks utilized in the sinking of oil wells, and the present application is a division of the application filed by me in the United States Patent Office on the 15th day of November, 1910, bearing Serial Number 592,422, and, in common with the invention therein described, the object of the present invention is to maintain the bearing boxes for the sheaves in true alinement and to permit of the same being readily and accurately adjusted and held securely locked in adjusted position relative to the crown blocks.

The crown block as at present constructed comprises wooden timbers arranged cross-wise of the wooden crown at the top of the derrick frame and to said crown block the bearing boxes for the multiplicity of derrick sheaves are bolted, with the result that as the strains of the cables working thereover are placed onto the bearing boxes the same sink or bite into the wooden supporting surfaces and the same get out of alinement, resulting in the sheaves tilting sidewise and causing an untrue running of the cables. This necessitates the sheave boxes being repeatedly blocked up—so to speak—in order to secure proper alinement, and, as the boxes are bolted directly to the wooden crown blocks it is a difficult matter to vary the adjustment thereof. Again, as the wooden crown blocks are not uniform, some being softer than others, it follows that one will give under the severe strains to which they are subjected quicker than the others, thus requiring constant attention to maintain the proper alinement of the sheave boxes. It is these recognized defects which the present invention is designed to obviate; and by so doing not only materially prolonging the life of the crown blocks, but providing for the permanent alinement of the sheave block and facilitating the adjustment to vary the position thereof relative to the said blocks.

To comprehend the invention reference

should be had to the accompanying sheets of drawings, wherein—

Figure 1 is a plan view of the crown blocks with the derrick sheaves positioned thereon. Fig. 2 is a side elevation of the parts disclosed by Fig. 1 of the drawings, one of the crown blocks and the oil derrick being broken away. Fig. 3 is an enlarged broken side elevation of one of the crown blocks, illustrating one of the bearing blocks held thereto and the sheave in position. Fig. 4 is a cross sectional view illustrating one of the sheaves, the bearing boxes therefor, and the crown blocks to which the said boxes are adjustably held.

In the drawings, the numeral 1 is used to designate the upright timbers of the oil derrick, 2 the strengthening strips, and 3 the built up crown timbers. On this crown are secured the transversely disposed metal I-beams 4, on which rest the spaced transversely extending metal crown blocks 5, which, like the beams 4, are composed of I-beams. To the face of each crown block is secured a longitudinally disposed metallic face or wear plate 6, which is formed with a dove-tailed channel or groove 7, which receives the heads of the securing bolts 8 for the sheave boxes 9, which are held thereto by the securing nuts 10; the journals 11 of the series of sheaves being secured to the bearing boxes by the box-caps 11. Between the spaced crown blocks work the series of derrick sheaves 12, 13 and 14, of which the ones 12 are commonly termed the "calf wheel crown" pulley, the one designated by the numeral 13 as the "crown" pulley and the one marked 14 as the "sand line" pulley.

The face or wear plates 6 are corrugated or fluted longitudinally to form a series of seats or indentations 15, with which register and interlock the transverse ribs 16 formed by the corrugated or fluted under surface of the bearing boxes 9, so that when the bolts 8 are tightened up the boxes will be securely locked in their adjusted position and held against movement or slippage relative to the crown blocks, the face or wear plates 6 being considered and treated as the upper surface of the crown blocks. To provide against lateral play or movement of the bearing boxes, each box is formed with a depending tongue 17, which fits snugly within the upper contracted portion of the longi-

tudinally disposed channel or groove 7 of the wear plates of the crown blocks, Fig. 4 of the drawings. Under this arrangement the bearing boxes are securely held against longitudinal and lateral movements, and as the crown blocks are composed of metal there can be no settling or sinkage of the bearing boxes into the crown blocks, hence the boxes cannot move out of alinement under the pulling strains placed onto the cable sheaves. The alinement of the sheaves is thus maintained, and inasmuch as the crown blocks are constructed of metal they are not materially affected by exposure to the weather, which prolongs the life of the derrick structure over those utilizing wooden crown blocks.

To change the adjustment of the sheaves relative to the crown blocks, it is only required to loosen the securing bolts 8, when the position of the bearing boxes may be quickly varied by moving each bearing box for the sheave to be changed in the desired direction to the required position, with the assurance that when the securing bolts are tightened up the bearing boxes will be in proper alinement.

By the use of the described invention perfect alinement of the bearing boxes for the sheaves is obtained, the excessive wear and tilting of the sheaves which follows from the use of wooden crown blocks is overcome, quick adjustment for the bearing boxes and, likewise, the ready attachment thereof to the crown blocks is obtained, the life of the derrick structure is materially prolonged,

and the upkeep reduced to a minimum, due to the fact that the expense incident to the constant repairs of the wooden crown blocks is dispensed with.

Having thus described the invention what is claimed as new and desired to be secured by Letters Patent is—

An adjustable bearing for well drilling rigs, comprising a pair of parallel spaced members, transversely corrugated wear plates held to the upper surface of each of said members and extending the full length thereof, said plates being provided on their upper surface and throughout their length with a longitudinally extending dove-tailed slot, bearing boxes arranged opposing each other on said plates and forming a pair, and said pair carrying a sheave, said bearing boxes formed on their under faces with transverse corrugations to register with the corrugations of said wear plates, lugs extending from the under surface of said bearing boxes for projection into said dove-tailed slots, and headed securing bolts slidably mounted in said slots and the shanks thereof extending through said bearing boxes for detachably securing the bearing boxes to the wear plates.

In testimony whereof I have signed my name to this specification in the presence of two subscribing witnesses.

JAMES T. HALL.
